UNITED STATES PATENT OFFICE.

WALTER A. SKINNER, OF BURNSIDE, CONNECTICUT.

LATH-PULLING MACHINE.

Application filed July 2, 1920. Serial No. 393,571.

To all whom it may concern:

Be it known that I, WALTER A. SKINNER, a citizen of the United States, and a resident of Burnside, in the county of Hartford and 5 State of Connecticut, have invented a new and Improved Lath-Pulling Machine, of which the following is a specification.

My invention relates to the class of devices employed for withdrawing lath or 10 similar supports from the tobacco stalks and upon which the latter have been impaled in the process of drying, and an object of my invention, among others, is to provide a device of this class that shall be simple in construction and particularly effective and 15 rapid in operation.

One form of device embodying my invention and in the construction and use of which the objects herein set out, as well as 20 others, may be attained, is illustrated in the accompanying drawings, in which—

Figure 1 is a view in side elevation of a tobacco stripping machine embodying my invention.

25 Figure 2 is a top view of the same.

Figure 3 is an end view, with the motor driving mechanism removed.

Figure 4 is the bottom view of the gripper device.

30 Figure 5 is an isometric view, scale enlarged, illustrating the operation of the device.

In its preferred form of construction my improved tobacco lath puller comprises a 35 frame made up of end supports and an intermediate support. One end support includes two posts 7 rising vertically from a base board 6 at opposite sides thereof and joined by a cross bar 8, while the other end support

40 comprises a post 9 rising vertically from the base board at one side thereof, a side post 10 extending diagonally upward from one side of the base board, a brace 11 and a cross bar 13. The intermediate support is similar

45 in construction to the end supports just described having in addition to the parts thus described a vertical post 14 secured at its opposite ends to cross bars 12 and 13, said cross bars 13 on the intermediate and 50 end supports extending diagonally upward from the side posts.

A rack for tobacco lath is arranged between an end support and the intermediate support, this rack comprising a bottom board 15 secured to the cross bar 8 and to the bottom cross bar of the intermediate

support with cleats 16 extending outwardly from the bottom board for the lath that fall from above after the tobacco has been stripped therefrom. Strips 17 extend upwardly from the bottom board to form a back for the rack.

The intermediate support and end supports together with the board 15, cleats 16 and the posts 17 form a stripper section of 60 the frame, which section also includes guide bars 18 extending lengthwise along opposite sides of the section at the top thereof, the bars and posts thus far described being preferably composed of angle iron, the bars 70 18 having the horizontal parts of the angle iron composing them projecting inwardly to form guides for a stripper to be hereinafter described.

The intermediate support and the end support comprising the post 9 make up a feed 75 section of the frame that also includes rests 19 secured to the upper sides of the upper top cross bars, these rests being of considerable width, and the end and intermediate 80 supports being spaced apart a distance to permit the ends of the lath to rest upon said rests, and sides 20 are provided as an aid in retaining the lath in place, said sides 85 and rests in fact providing a sort of trough in which the lath are placed with the tobacco (stems and leaves) depending through the bottom of said trough. This trough slants downwardly from the feeding or front 90 side of the frame, and the rests are preferably so positioned that that part thereof in line with a line drawn centrally between the guide bars 18 will be substantially in the horizontal plane of the guides on said guide bars.

The stripper comprises a slide including a base 21 with guideways 22 thereon, the latter, in the structure herein shown, being formed by riveting strips of metal to the upper side of the base to provide grooves 100 constituting said guideways, and as shown in Figure 4 of the drawings. Gripper jaws 23 are pivotally supported on the under side of the base 21 these jaws each being preferably of angular shape with the vertical part constituting the gripper jaws proper. Connecting bars 24 are pivotally attached at their ends to the gripper jaws, the opposite ends of said bars being pivotally connected to a gripper jaw actuating bar 25 105 having a slot to receive studs projecting from the base. This actuating bar receives 110

a connecting rod 27 that is pivotally attached to a gripper operating lever 28 pivotally secured at its lower end to the base board 6. A pitman 29 connects the lever 28 with a crank pin 30 on a wheel 31 and by means of which the grippers are actuated. This wheel 31 is secured to a shaft forming part of a reducing mechanism located in a case 32, said reducing mechanism being 5 driven as by means of a motor 33 located on top of the case 32, this motor preferably being of the internal combustion engine type, but it will be understood that any means for applying power to the grippers 10 may be employed as conditions may require.

A stop bar 34 is secured to the ends of the guide bars 18 and to the side of one of the rests 19, as shown in Figure 5 of the drawings, this stop bar serving as a stop to engage the tobacco stems and hold them 20 against movement when the lath are being withdrawn from the incision within the stem.

In the operation of the device the lath on 25 which the tobacco is hung are placed in numbers on the rests 19 with the tobacco hanging from the lath. These lath are placed in succession with the ends that rest on the intermediate support in line with the opening between the gripper jaws that are 30 reciprocated by the mechanism hereinbefore described so that they will pass across and slightly beyond the intermediate support and the ends of the lath on this support. As the grippers approach the end of their path 35 of movement forwardly or toward the lath the ends of the latter are received between the gripper jaws, that, at this time, are open, said jaws having been opened by the operation of the actuating bar 25 moving forwardly on the base 21, which forward movement was permitted by the studs engaging a slot 26 and comprising the connection between said bar and said base, at the time 40 said bar commenced its movement to operate the grippers. In the reverse movement of the grippers as the actuating bar 25 begins its backward movement, or movement away 45 from the lath, the stud and slot connection with the base 21 causes the first part of said movement to be independent of said base, the latter remaining stationary, with a result that the connection of the actuating bar with the grippers causes the latter to be closed upon the latter before the base 21 50 begins to move backwardly. When the forward stud is located in the forward end of its slot the base 21 begins to move backwardly, drawing the lath and tobacco thereon with it until the upper end of the tobacco stem nearest the stop bar 34 is drawn 55 against said bar. A continued pull upon the lath causes the stems to be drawn together and the lath is drawn through the stems and to a position overlying the rack 60 in the stripper section of the frame. As 65

the stripper begins its return or forward movement the jaws are opened as hereinbefore described and the lath is released and drops on to the bottom board 15, after which the operation is repeated.

It is noted that the angular arrangement of the jaws 23 with respect to each other provides a flaring opening widest at its end nearest the lath to receive the lath ends.

I claim:

1. A tobacco stripping machine including rests spaced apart to receive the ends of lath with tobacco depending between them, said rests being disposed in an inclined plane, a stop overlying one of said rests providing a space between said rest and the stop for movement of the end of a lath, and a stripper including a pair of jaws movably mounted with the opening between the jaws in line with the end of a lath supported on 80 said rests and underneath said stop.

2. A tobacco stripping machine including a frame comprising two sections, rests disposed in an inclined plane on one of said sections and spaced apart to receive the 90 ends of lath thereon with tobacco depending between them, and a stripper reciprocatingly mounted on the other section of the frame and comprising jaws located in line with the end of a lath located upon said 95 rest near the lower end thereof.

3. A tobacco stripping machine including a frame comprising two sections, rests located on one of said sections and extending laterally of the frame at the side 100 thereof and spaced apart to receive lath with tobacco depending between said rests, a stripper comprising jaws reciprocatingly mounted on the other section of said frame and with an opening between said jaws in line with a lath located near the inner end 105 of said rests, and cleats located on the second section of the frame and underlying said stripper to receive lath therefrom as they are stripped from the tobacco and 110 released from said jaws.

4. A tobacco stripping machine including a frame, rests extending laterally from one side of the frame and spaced apart to receive the ends of lath with the tobacco depending between them, a stripper including jaws reciprocatingly mounted in line with a lath located on said rests within the main part of the frame, cleats extending laterally beyond one side of the frame with 115 their ends underlying said stripper to receive the lath as they are released from said jaws, and means for operating the stripper.

5. A tobacco stripping machine including a base movably mounted, a pair of jaws each of which is pivotally mounted on a pivot located in a fixed position on the base, an actuating bar movable independently of 120 said base to effect operation of said jaws,

means for actuating said bar, and a connection between said bar and each of said jaws to operate the latter.

6. A tobacco stripping machine including
5 a movably mounted base, a pair of jaws of angular shape and comprising a base portion and a vertical portion, the latter serving as grippers, means for pivotally connecting the base portion of the jaws to
10 the gripper base, an actuating bar loosely connected with the gripper base and movable independently thereof to effect operation of said jaws, means for operating the bar, and a connection between said bar and
15 each of said jaws to operate the latter.

7. A tobacco stripping machine including spaced rests for the ends of the lath with the tobacco thereon depending between said rests, a stop to resist movement of the
20 tobacco, a gripper comprising movably mounted jaws to grip said lath, and means to operate said jaws to cause them to engage said lath and withdraw them from the tobacco.

25 8. A tobacco stripping machine including a frame, a rest arranged laterally of said frame to receive the ends of tobacco lath, a

gripper movable lengthwise of the frame and comprising jaws to grip said lath, and a rack to receive the lath after they are 30 withdrawn from the tobacco.

9. A tobacco stripping machine comprising a frame including an end support, an intermediate support, guide bars extending between said supports, a gripper slidably 35 mounted on said guide bars, means for reciprocating said gripper, a second end support, and rests on the last named end support and on the intermediate support for the ends of tobacco lath. 40

10. A tobacco stripping machine comprising a frame including an intermediate support, guide bars secured to said intermediate support, a gripper movably mounted on the guide bars and including 45 gripper jaws, means for operating said gripper, an end support, rests located on said end support and said intermediate support, and a stop bar secured to said guide bars and spaced above said rests in 50 the path of movement of the stem of tobacco leaves supported on lath engaged by said grippers.

WALTER A. SKINNER.
